UNITED STATES PATENT OFFICE.

THEODORE L. NEUMANN, OF DAYTON, OHIO, ASSIGNOR OF ONE-HALF TO
THE DAYTON PAPER NOVELTY COMPANY, OF DAYTON, OHIO, A COR-
PORATION.

PAPER PAIL.

SPECIFICATION forming part of Letters Patent No. 783,643, dated February 28, 1905.

Application filed June 27, 1904. Serial No. 214,279.

To all whom it may concern:

Be it known that I, THEODORE L. NEUMANN, a citizen of the United States, residing at Dayton, in the county of Montgomery and State 5 of Ohio, have invented certain new and useful Improvements in Paper Pails, of which the following is a specification.

My invention relates to a paper pail adapted to hold oysters, ice-cream, and other similar commodities.

The object of my invention is to produce a tight-jointed and a strong compact vessel.

The features of the invention are more fully set forth in the description of the accompanying drawings, forming a part of this specification, in which—

Figure 1 is a plan view of the scored blank, which is adapted to be folded into the pail. Fig. 2 is a sectional perspective view showing one side of the pail in a partially-folded condition. Fig. 3 is a central vertical section showing one side of the pail in a folded position with the cover open. Fig. 4 is a perspective view of the completed pail, showing 25 a modified form of folding.

A represents the bottom of the pail.

B B' represent the ends of the pail to which the cover extensions H H' are attached.

C C' represent the opposite or right-angled 30 sides of the pail, to each of which are attached the folding-over or sealing flap L. The side C is connected to the side B by means of the diagonal side-wall folds E E' and D D'. These side-wall folds are connected by the 35 corner-folds I J to the cover H. On the opposite side of the blank are the counterpart of these folds E' D' I' J', cover H' being duplicate and adapted to overlap cover H. The corner-folds on the opposite sides of the pail, 40 connecting the sides C' to the sides of the cover, are a duplicate of the parts already described.

K represents slits formed in the four-cornered folds J J' on each side of the blank to receive a clip which is passed through these 45 slits and secures the cover together in the usual manner. The bail M is hooked through the orifices a of the respective triangular folding sections D E and D' E' and sides C C'. The bail holds the pail in its folded po-

sition. The covers H H' are adapted to open 50 out and fold under the bail in its upright position.

It will be observed that in the blank herein shown and described the sides C C' are scored in right lines with the scored lines of the bottom A, while the ends B B' are scored tapering. Now in order that the sides formed by the blank portion C E D E' D' may likewise form taper sides the blank is prepared in the following manner: The free edges of the folds 55 E E' are in right line with the edge of the side C in a plane with the scored line of the flap L. In the form shown the triangular folding section D at its widest edge is increased in dimension over the free edge of wall E a 60 length equal to the amount of taper of the side wall B, thus forming an equal taper to the ends of the pail.

In order that the sides may be sealed against leakage of the liquid in the pail, the flap L 70 folds over the edge of side fold E, as shown in Fig. 3.

In Fig. 2 the fold is such that the side C is the inner folded wall of the pail, the diagonal side folds E and D forming the outer wall 75 of the pail. This form of folding may be reversed, as shown in Fig. 4, and the side C may form the outer wall of the pail. The fold E rests against it and the fold D forming the inner wall of the pail, the flap L being 80 bent over the edge of fold E' inwardly, so as to seal the pail against leakage.

It will be observed that the blank is substantially rectangular, that the ends B B', the sides C C', and the bottom A are substantially 85 rectangular, and that the corner-sections between the sides and ends, respectively, are rectangular, but each divided into two triangular folding sections by the diagonal scored lines extending from each corner of the bottom to each outer corner of the blank. The terms "sides" and "ends" are merely arbitrary, the sections C C' being called "sides" to identify them as the sections against which the triangular sections D D' E E' fold. It 90 will be noted that the outer ends of the sides and the outer edges of the adjacent triangular folding sections E E' are of equal width.

By this construction the folding tucks L of the sides may fit and fold over perfectly either one or both of the sides of the sections E E', whether they are folded against the inside or 5 the outside of the sides C C'. This gives great convenience in folding and makes a perfect sealed side at the top, without joint or seam, in each of the several possible folding positions of the blank. It will be noted that 10 the outer edges of the side section C' and its adjacent folding sections E E' form a straight line across the side of the blank and that this is also true of the sections C E E'. By reason of this fact, and also the fact that the 15 outer edges of the sections above named are of equal width, when the blank is folded these meeting outer edges come together in a straight line across the top, over which the tucks L fold. It will also be noted, as shown 20 in Fig. 4, that by reason of the straight scored lines forming the section C C' the sides of the pail are formed by the side sections C C' and their respective overlapping portions of their 25 adjacent folding sections D D' and E E', the said parts being held together by the tucks L.

By making the edge of the triangular sections E E' of the same dimension as the folding flap L, I am able to seal the pail without slitting the edges of the folds E and E', thereby 30 weakening the wall and rendering the pail liable to leakage and less durable than the form herein shown.

The term "scoring" in this specification is the equivalent of creasing in preparing the 35 blank for folding.

Having described my invention, I claim—

1. A blank for a paper pail having scored lines forming two ends, two side sections and a bottom, the four sections intermediate of 40 the sides and ends respectively, having diagonal scored lines dividing them into two triangular sections each, adapted to fold upon one another and against two opposite sides when the blank is bent into shape, the outer edges 45 of said two opposite sides and the outer edges of the triangular sections adjacent to said sides

being of equal width, and folding tucks formed across the outer edges of said opposite sides adapted to fit and fold over the outer edges of said adjacent folding sections. 50

2. A blank for a paper pail having scored lines forming two ends, two side sections and a bottom, the four sections intermediate of the sides and ends respectively, having diagonal scored lines dividing them into two triangular sections each, adapted to fold upon one another and against the two opposite sides when the blank is bent into shape, the outer edges of said two opposite sides and the outer edges of the triangular sections adjacent to 60 said sides being of equal width and forming straight lines across the opposite sides of the blank, and folding tucks formed across the outer edges of said opposite sides adapted to fit and fold over the outer edges of said adjacent folding sections. 65

3. A blank for a paper pail having scored lines forming two ends, two side sections and a bottom, the scored lines forming the side sections being straight across the blank, and the 70 scored lines forming the ends being tapered outwardly from the bottom, the four sections intermediate of the sides and ends respectively, having diagonal scored lines dividing them into two triangular sections each, adapted to 75 fold one upon another and against the two opposite sides when the blank is bent into shape, the outer edges of said two opposite sides and the outer edges of the triangular sections adjacent to said sides being of equal width and forming straight lines across the opposite sides of the blank, and folding tucks formed across the outer edges of said opposite sides adapted to fit and fold over the outer edges of said adjacent folding sections. 80

In testimony whereof I have hereunto set my hand.

THEODORE L. NEUMANN.
